UNITED STATES PATENT OFFICE.

JAS. G. ABBOTT AND A. LAWRENCE, OF PHILADELPHIA, PENNSYLVANIA.

STOVE.

Specification of Letters Patent No. 25,612, dated October 4, 1859.

To all whom it may concern:

Be it known that we, J. G. ABBOTT and ARCHILUS LAWRENCE, of Philadelphia, in the county of Philadelphia and State of Pennsylvania, have invented a new and useful Improvement in Gas-Burning Stoves; and we do hereby declare that the following is a full, clear, and exact description of the same, reference being had to the annexed drawing, forming part of this specification, in which—

Figure 1 is a vertical section of ring and door, Fig. 2 is a horizontal section of same.

In the drawing R is the air ring around which the sheet iron cylinder is fixed. It receives its supply of air through the openings a and discharges it through the small open-

ings o in the usual way. The openings a are made through the lower portion of the door frame F and are closed by a slide B.

We claim—

The combination of the ring R, perforated door frame F extending down over the ring and slide B with the stove cylinder, as set forth.

In testimony whereof we have hereunto signed our names before two subscribing witnesses.

JAMES G. ABBOTT.

ARCHILUS LAWRENCE.
